(57) **CLAIM**

The ornamental design for a toilet tissue roll holder tube, as shown and described.

DESCRIPTION

FIG. 1 is a front perspective view of a toilet tissue roll holder tube showing our design;

FIG. 2 is an elevational view thereof; and,

FIG. 3 is a left side elevational view thereof, the right side elevational view being a mirror image thereof.

The broken lines in the Figures are for illustrative purposes only and form no part of the claimed design.
